METHOD OF PREPARING POLYARYL SELENAZOLES

Edmund B. Middleton, Woodbridge, and George A. Dawson, Stelton, N. J., assignors, by mesne assignments, to E. I. du Pont de Nemours & Company, Wilmington, Del., a corporation of Delaware

No Drawing. Application October 25, 1939,
Serial No. 301,296

8 Claims. (Cl. 260—298)

This invention relates to new and useful polyaryl selenazole compounds and to a new and improved method for producing such compounds. The invention is particularly concerned with the production of selenazole derivatives containing a beta naphthoselenazole nucleus, which are new compounds exceedingly difficult to prepare.

The term "polyaryl selenazole" is used to describe polyheteroatomic ring compounds containing two or more condensed benzene rings and containing nitrogen and selenium in the heterocyclic ring structure as the hetero atoms.

Many of the simple azoles consisting of a single ring nucleus have been known for years. Hantzsch (Ber. 21, 945) described a 2-methyl oxazole in 1888. The 2-methyl thiazole bases have also been known since 1888 (Annalen, vol. 250, pp. 257-280). A 2-methyl selenazole base was described by Hoffman, Annalen der Chemie 250, 314-320.

The base 2-methyl benzoxazole was described in 1876 by Ladenburg, Ber. 9, 1924. The 2-methyl benzothiazole base has been known since 1880, Hoffman, Ber. 13, 1236. The 2-methyl benzoselenazole base has been known since 1928, Clark, J. C. S. (1928) pp. 2313-20.

Of the naphthoxazoles, the 2-methyl alpha naphthoxazole base has been known since 1883, Ber. 16, 1933. The 2-methyl alpha naphthothiazole base has been known since 1898, Ber. 20, 1800. According to British Patents Nos. 386,791 and 389,969, pseudocyanine and isocyanine dyes can be made from the methyl salts of 2-methyl alpha naphthoselenazole, although the properties of the base are not described. The latter patent indicates that this base can be made from 1-amino-2-nitro naphthalene by diazotization followed by treatment with potassium selenocyanide to replace the diazo group by the group SeCN, then reducing the resultant product by means of sodium hydrosulfite in the presence of caustic potash to produce 2-amino-1-seleno naphthol, oxidizing this compound to 2:2'-di-amino-1:1'-dinaphthyl diselenide, and treating the latter with zinc and acetic anhydride to produce 2-methyl-alpha-naphthoselenazole.

While it is theoretically possible to produce the compounds mentioned, the series of reactions described, when applied to polyaryl derivatives such as amino nitro naphthalenes, present so much difficulty as to be impractical commercially, and the present applicants have, therefore, sought to develop a new process for the manufacture of 2-methyl naphthoselenazoles. In the case of 2-methyl alpha naphthoselenazole, they

have developed a new and more practical method than that of British Patent No. 389,969. This method is described in their co-pending United States patent application Serial No. 78,734. With respect to 2-methyl-beta-naphthoselenazole, which is a new compound, not hitherto described elsewhere, they have developed the process which is a subject of this application.

It may be observed that the difficulty of reaction resulting in the production of azoles containing members of the oxygen group of elements in the azole ring may vary greatly with different elements, becoming greater in proceeding from the non-metallic elements such as oxygen and sulfur to the more strongly metallic elements such as selenium and tellurium. This probably accounts for the fact that many of the oxazoles and thiazoles have been known for years while the preparation of most of the selenazoles has been accomplished more recently and some of them are still unknown even though the corresponding oxazoles and thiazoles are known. Furthermore, the tellurazoles from the simplest to the more complex derivatives have not been described up to the present time.

As a general rule, moreover, the more complex the compound and the heavier its molecule, the more difficult it is to prepare. Thus, a naphthoselenazole is more difficult to prepare than a benzoselenazole. Additionally, a general type of reaction which can be used in making one compound often cannot be used in making a closely related compound. For example, we have prepared the base alpha naphthoselenazole by several series of reactions, but the same series of reactions could not be used conveniently to produce the isomeric beta naphthoselenazole base.

One of the objects of this invention is the provision of a new and improved, commercially practicable series of reactions for producing new and useful compounds containing a beta naphthoselenazole nucleus.

A more specific object has been the preparation for the first time of the base beta naphthoselenazole and quaternary salts thereof. Other objects will appear hereinafter.

These objects are accomplished in accordance with this invention by reacting a selenohydrate, preferably sodium or potassium selenohydrate, upon an alpha nitro-beta-halogeno-naphthalene compound in a non-oxidizing atmosphere, preferably in an atmosphere of hydrogen, and treating the resultant reaction product with a reducing agent capable of reducing a nitro group to an amino group, preferably a metallic reducing

agent, such as zinc, and an acid anhydride of an aliphatic carboxylic acid, for example, acetic anhydride, thereby forming a beta-naphthoselenazole. The reduction of the nitro group to the amino group and closing of the selenazole ring occur simultaneously or contemporaneously.

The general equations illustrating the course of reactions starting with beta-amino-naphthalene may be illustrated as follows:

where R=lower alkyl groups.

The above equations are intended to represent generally the course of the reactions, but it will be understood that the process of the invention contemplates the particular steps involved, regardless of whether the foregoing equations represent all of the reactions taking place.

In this way, it has been possible for the first time to prepare the base 2-methyl beta-naphtho-selenazole and other compounds containing a selenazole nucleus, from 1-nitro-beta-naphthoselenazole nucleus, from 1-nitro-2-chloro-naphthalene. This compound has the general formula:

It is obtained as cream colored crystals melting around 102°-104° C.

The following examples in which the quantities are stated in parts by weight will serve to further illustrate the invention but are not intended to limit it.

EXAMPLE I

Preparation of 2-methyl beta-naphthoselenazole

Twenty-five (25) parts of 1-nitro-2-chloro-naphthalene was dissolved in about 160 parts of ethyl alcohol in a three neck vessel equipped with a stirrer reflux condenser and gas inlet tube that ran to the bottom of the vessel. A solution of potassium selenohydrate (KSeH) was prepared by dissolving 6.8 parts of potassium hydroxide in about 80 parts of ethyl alcohol and saturating it at 15° C. with H₂Se. The H₂Se (hydrogen selenide) was generated by dropping very dilute hydrochloric acid upon aluminum selenide (Al₂Se₃).

The vessel containing the nitro-chlor-naphthalene solution was filled with hydrogen to the

complete exclusion of air, and then while stirring, the KSeH solution was added rather quickly down the condenser. Heat was generated and the vessel was cooled to control the reaction.

With the subsidence of the reaction, the vessel was warmed with steam for one hour. The stirrer and reflux condenser were then removed and the contents evaporated to dryness with the aid of steam and vacuum.

Acetic anhydride (216 parts) was then added. The hydrogen line was removed and the reflux condenser replaced. The solution was heated to reflux and reduced with 35 parts of zinc dust. Refluxing was continued for one hour after the zinc had been added. The reaction took place violently and the zinc was added at intervals in very small portions. After reduction was complete, the solution was cooled and filtered, and the filtrate vacuum distilled. The distillate be-

20 low

150° C./²⁰ m

was discarded and the fraction distilling from 150°-220° C. was redistilled, the distillate finally 25 collected being from

175°-205° C./²⁰ m

30 The distillate was a yellow oil that soon crystallized. When recrystallized from alcohol, the base 2-methyl beta-naphthoselenazole was obtained as cream colored crystals melting from 102°-104° C.

35 Nitro-chlor-naphthalene for this reaction may be prepared by the Sandmeyer reaction upon diazotized nitronaphthylamine according to the method of Hodgson and Walker, J. C. S. (1933), p. 1620.

40 Aluminum selenide may be prepared by mixing together intimately calculated quantities of powdered aluminum and selenium and igniting the reaction by magnesium ribbon or a mixture of sulfur and potassium chloride. The reaction 45 is best conducted at a safe distance. It is dangerously violent and care should be taken not to breathe too deeply of the fumes.

45 The 2-methyl beta-naphthoselenazole base forms quaternary salts by reaction with esters of 50 organic and inorganic acids, e. g., dimethyl sulfate, diethyl sulfate, ethyl paratoluene sulfonate, ethyl iodide, methyl iodide, propyl iodide, ethyl bromide, methyl bromide, propyl bromide, allyl iodide, allyl bromide and the corresponding chlorides and perchlorates as well as higher alkyl homologues. These compounds have the following general formula:

55 in which R is alkyl (e. g., methyl, ethyl, propyl) and X is a salt forming radical (e. g., chlorine, bromine, iodine, methsulfate, ethsulfate, perchlorate, etc.).

60 These new compounds may be used to make new and useful dyes which may be employed for various purposes, e. g., for dyeing materials and in photography for addition to photographic emulsions as sensitizers and for other purposes.

The following examples are given as typical of the use of these new compounds in preparing new and useful dyes:

EXAMPLE II

Preparation of 3:3'-dimethyl beta naphthoselenocarbocyanine bromide

One part of the base 2-methyl beta naphthoselenazole and about .5 part of dimethyl sulfate were heated in a sealed tube for three days at 95° C. The melt was then dissolved in 20 parts of pyridine and 2.7 parts of ethyl orthoformate. Upon heating this solution to reflux a green-blue color developed. After one hour refluxing the solution was treated with excess aqueous potassium bromide solution and cooled. The dye was obtained as fine purple crystals which were recrystallized twice from alcohol.

When tested in silver halide photographic emulsions, this dye showed pronounced sensitizing properties, being a relatively weak sensitizer for silver bromide emulsions containing a small amount of silver iodide but a very powerful sensitizer in silver chloride emulsions, sensitizing in the red region of the spectrum with a blind spot in the green region.

EXAMPLE III

Preparation of 3-methyl-1-ethyl beta naphthoselenazole pseudocyanine iodide

One part of 2-methyl beta naphthoselenazole prepared as in Example I was heated with .54 part of dimethyl sulfate for three days in a sealed tube at 95° C. The melt was then dissolved in 20 parts of absolute alcohol and 1.2 parts of methylthiocarbostyryl ethiodide were added to the solution which was heated to reflux and treated with 0.5 part trimethylamine. A red color developed and after one hour, refluxing was discontinued and the solution cooled. Red crystals of the dye separated, were filtered and recrystallized twice from alcohol. Their alcoholic solution was similar in color to that of erythrosine. This dye also exhibited marked sensitizing power in silver halide photographic emulsions.

The invention is subject to variations and modifications in the manner of its practical application. The beta naphthoselenazole base and salts thereof may contain a substituent other than methyl in the 2-position, e. g., a higher alkyl group such as ethyl. This may be accomplished by using chemically equivalent proportions of propionic anhydride or a higher homologue instead of acetic anhydride in the previously described reactions.

The procedure for making the nitro amino naphthalene described generally in the first series of Equations 1 may be carried out in a known

manner by first acylating the amino to block any reaction of the nitrating acid with the amino group, and then nitrating the acylamino naphthalene to produce a nitro-acylamino naphthalene. Hydrolysis of this product in a known way splits off the acyl group leaving the nitro amino naphthalene.

In the second series of reactions 2, the halogen atom of the nitro-halogeno naphthalene may be chlorine, bromine or iodine. A solvent or reaction medium which is substantially inert, for example, alcohol, is preferably used in carrying out the third series of reactions 3. Other inert solvents may be used. Other metallic selenohydrates may also be used, although the alkali metal selenohydrates are preferred. Temperatures at which refluxing will occur in the fourth series (4) will be determined largely by the specific acid anhydride employed. Thus, the temperature of refluxing will be higher with propionic anhydride than with acetic anhydride. The temperature employed in any case should be insufficiently high to cause the desired products to be destroyed by decomposition. If it is desired to reduce the refluxing temperature, a lower pressure may be employed.

The steps of the process, and the series of reactions herein described, are applicable to the preparation of any beta naphthoselenazole base and the quaternary salts thereof.

The invention makes possible the preparation of an entirely new series of compounds having a wide variety of uses, for instance, as dye intermediates, dyes, sensitizers for photographic emulsions and for other purposes.

Having thus described the invention, what we claim as new and desire to secure by Letters Patent of the United States is:

1. In a method of making a beta naphthoselenazole, the steps which comprise treating an alpha nitro-beta-halogeno naphthalene with a selenohydrate in a non-oxidizing atmosphere, and treating the resultant reaction product with a reducing agent capable of reducing a nitro group to an amino group and with an anhydride of an aliphatic carboxylic acid.

2. In a method of making a beta naphthoselenazole, the step which comprises treating a 1-nitro 2-halogeno naphthalene with an alkali metal selenohydrate in an atmosphere of hydrogen and treating the resultant product with zinc and acetic anhydride.

3. In a method of making the base 2-methyl beta naphthoselenazole, the steps which comprise treating 1-nitro 2-chloro naphthalene with potassium selenohydrate in alcohol solution in an atmosphere of hydrogen while cooling the reaction mixture, then evaporating the resultant reaction product to dryness, mixing acetic anhydride therewith and adding zinc in finely divided form while refluxing, then cooling, filtering and vacuum distilling the filtrate, thereafter redistilling the fraction of the filtrate boiling from 150° to about

220° C./ $\frac{20}{m}$

to collect that fraction of the filtrate boiling from about 175° to about

205° C./ $\frac{20}{m}$

and separating the 2-methyl beta naphthoselenazole base from said fraction by crystallization.

4. In a method for the preparation of a beta

naphthoselenazole, the steps which comprise treating an alpha-nitro-beta-chloronaphthalene with an alkali metal selenohydrate in a non-oxidizing atmosphere and treating the resultant reaction product with a reducing agent capable of reducing a nitro group to an amino group.

5. In a method for the preparation of a beta naphthoselenazole, the steps which comprise treating an alpha-nitro-beta-halogeno naphthalene with an alkali metal selenohydrate in a non-oxidizing atmosphere, and treating the resultant reaction product with a reducing agent capable of reducing a nitro group to an amino group.

6. In a method of making a 2-methyl beta naphthoselenazole, the steps which comprise 10 treating 1-nitro 2-chloro naphthalene with a selenohydrate in a non-oxidizing atmosphere, and treating the resultant reaction product with a

reducing agent capable of reducing a nitro group to an amino group and with acetic anhydride.

7. In a method of making a 2-methyl beta naphthoselenazole, the step which comprises treating 1-nitro 2-chloro naphthalene with an alkali metal selenohydrate in an atmosphere of hydrogen, and treating the resultant product with zinc and acetic anhydride.

8. In a method of making a 2-methyl beta naphthoselenazole, the step which comprises treating a 1-nitro 2-halogeno naphthalene with potassium selenohydrate in an atmosphere of hydrogen in the presence of a substantially inert solvent medium, and treating the resultant product with zinc and acetic anhydride.
